US0D1104741S

(12) **United States Design Patent** (10) **Patent No.:** **US D1,104,741 S**
(45) **Date of Patent:** **** Dec. 9, 2025**

(54) **CONTAINER**

- (71) Applicant: **Kraft Foods Group Brands LLC**, Chicago, IL (US)
- (72) Inventors: **Audrey Rose Flood**, Chicago, IL (US); **Trevor Allen Boukamp**, Chicago, IL (US); **Maxine J. Roman**, Chicago, IL (US); **Michael D. Putnam**, Seattle, WA (US)
- (73) Assignee: **Kraft Foods Group Brands LLC**, Chicago, IL (US)
- (**) Term: **15 Years**
- (21) Appl. No.: **29/997,434**
- (22) Filed: **Apr. 8, 2025**

Related U.S. Application Data

- (62) Division of application No. 29/809,708, filed on Sep. 29, 2021, now Pat. No. Des. 1,074,426.

CLAIM

The ornamental design for a container, as shown and described.

DESCRIPTION

FIG. 1 is a top, front perspective view of a container in accordance with our new design;

FIG. 2 is a bottom, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included for the purpose of illustrating the unclaimed portions of the container and form no part of the claim.
